FASTENING-INSERTING MACHINE

Alfred Neumann, St. Louis, Mo., assignor to
United Shoe Machinery Corporation, Paterson,
N. J., a corporation of New Jersey

Application December 23, 1937, Serial No. 181,329

7 Claims. (Cl. 1—41)

This invention relates to fastening-inserting machines and is herein illustrated in connection with a device for supporting and guiding a shoe in operative position relatively to fastening-inserting mechanism.

In some types of shoes one or more rows of fastenings are driven through the outsole and into the insole at the shank portion of the shoe in order to reinforce said shank portion for the purpose of stiffening it and for preventing ripping of the threads caused by relative sliding movement between the outsole and insole. Such rows of fastenings are also sometimes driven into the shoe to provide ornamentation.

It is an object of the invention to provide an improved shoe support and gage by which a shoe can be readily advanced past fastening-inserting mechanism to receive one or more rows of such fastenings evenly spaced from the edges of the outsole.

To this end and as illustrated, I have provided, in a machine of the type referred to, a support adapted to enter the welt crease or shank crease of a shoe and a gage mounted upon the support for engaging the edge of the sole of the shoe to position the same in operative relation to a fastening-inserting tool, the support and gage preferably being adjustable laterally relatively to each other and to the tool so that the spacing of a row or rows of fastenings driven into the sole of the shoe can be readily varied.

These and other features of the invention are disclosed in the following specification and in the accompanying drawing and are pointed out in the appended claims.

In the drawing

Fig. 1 is a view in side elevation and partly in section of a portion of a fastening-inserting machine embodying one form of my invention;

Fig. 2 is a detail view in side elevation of the shoe support and gage;

Fig. 3 is a top plan view of the shoe support and gage; and

Fig. 4 is a detail view partly in section showing the manner in which the gage and support engage the shoe.

Fig. 1 illustrates a portion of a machine for driving fastenings such as wooden pegs or nails in shoes. This machine comprises a frame 10 having a spindle 12 which carries a horn 14 arranged to be moved heightwise of the machine in presenting a shoe 16 with the sole 17 thereof in engagement with the horn to fastening-inserting mechanism including a presser plate 18 and a tool diagrammatically indicated by refer-

ence character 20. The fastening-inserting mechanism which is not herein illustrated in detail may be of any suitable construction such as that shown and described in United States Letters Patent No. 581,066, granted April 20, 1897, 5 upon an application filed in the names of J. F. Davey and S. W. Ladd.

In order to support a shoe to be operated upon against the thrust of the fastening-inserting tool I have provided a supporting member in the form of a plate 22 slidably mounted in a groove 24 in the upper end of the horn 14. This support has a wedge-shaped nose portion 26 which is adapted to enter the shank crease or the welt crease of a shoe to be operated upon to engage the under side of the sole or the welt to support the shoe. The supporting member or plate 22 is movable laterally of the tool 20 for purposes of adjustment and can be locked in adjusted position by means of a capstan screw 28 extending through an elongated slot 30 in the plate 22 and into the body portion of the horn, the screw being readily operated by means of a pin or handle 32.

I have provided a gage 34 for contacting with the edge portion of the sole of a shoe in position upon the supporting member 22 for locating the shoe with the edge of the sole in predetermined position laterally of the tool 20. This gage 34 is in the form of a plate slidably mounted upon the supporting member 22 and arranged to be secured in fixed relation thereto by a bolt 36 which extends through an elongated slot 38 in the gage and into the supporting member. The screw 28 also passes through the slot 38 and the head of the screw engages the upper surface of the gage 34 in securing the plate 22 and the gage 34 in adjusted position. The gage 34 is normally moved with the supporting member 22 and it can be located with the member in various positions laterally of the tool 20, thus to provide for means for spacing from the edge of the sole of the shoe a row or rows of fastenings to be driven in the sole of the shoe.

Since it is sometimes desirable to drive two spaced rows of fastenings into a shoe, for example along the shank portion thereof, I have provided means for readily locating the gage 34 in either of two predetermined positions. To this end the supporting member 22 is provided with a downwardly projecting portion 40 which carries a screw 42 which acts as a stop to engage a flat portion 44 on the horn to limit outward movement of the supporting member and gage. The position of this stop screw 42 can be adjusted

and the screw can be locked in adjusted position by the nut 46. To limit inward movement of the supporting member and gage there is a stop screw 48 extending through the depending portion 40 and into the horn. The screw 48 has a head 50 which is adapted to engage the depending portion 40 when the supporting member 22 is moved to the left in Fig. 2. The position of the head can be adjusted by rotating the screw 10 48 which can be locked in adjusted position by a nut 52. Thus it will be seen that by releasing the locking screw 28 the supporting member 22 and gage 24 can be adjusted in either direction between two limiting positions determined by the 15 positions of the screws 42 and 48. By this mechanism the gage 34 can be positioned to locate a shoe relative to tool 20 for spacing the fastenings to be driven at any desired distance from the edge of the sole of the shoe and can rapidly be shifted to either of two predetermined positions.

The horn 14 is supported in a bracket 54 secured to the upper end of the spindle 12 and is arranged for movement heightwise of the machine in locating a shoe against the presser plate 18 adjacent to the tool 20. The spindle 12 is normally held in elevated position by a system of links 56, there being a treadle 58 secured by links 60 to the lower end of the spindle 12 for depressing the spindle to permit insertion or removal of a shoe between the supporting member 22 and the presser plate 18.

In driving the fastenings into the shoe it is desirable that the latter be held with its sole lying in a plane substantially at right angles 35 to the line of action of the tool 20. To assist the operator in accomplishing this, I have provided an auxiliary supporting member comprising a roll 62 carried at the upper end of an arm 64 pivotally mounted at 65 upon the bracket 54. 40 The roll is adapted to enter the welt crease or shank crease of the shoe at a point upon the opposite side of a shoe from that engaged by the supporting member and cooperates with the latter to maintain the shoe with its bottom substantially normal to the line of action of the tool 18. The roll 62 is carried by a shank 66 which is adjustable heightwise of the arms 64, the shank being held in adjusted position by two bolts 68 which extend through an elongated slot 70 in the arm 64 and into the shank 66.

The arm 64 is normally forced about its pivot 65 in a counterclockwise direction (Fig. 1) thereby to urge the roll 62 toward the support 22. This is accomplished by spring 72 which extends 55 between an ear 74 on the bracket 54 and an ear 76 on the arm 64.

In the operation of the machine the treadle 58 is depressed and a shoe such as shoe 16 is positioned upon the supporting member 22 with the 60 nose 26 thereof extending into the shank crease or welt crease of the shoe and with the edge of the sole in engagement with the gage 34 and the roll 62 in engagement with the opposite side of the shoe. The treadle is released with the result 65 that the horn is elevated to present the shoe to the presser plate 18 and the shoe is advanced past the fastening-inserting tool 20 which drives a row of fastenings through the outsole and into the insole along one side of the shoe. The shoe is then reversed and the same operation performed 70 upon the other side of the shoe. If it is desired to drive a second row of fastenings the supporting member 22 and gage 34 are moved to the right or left as the case may be and the operation 75 repeated.

Having described my invention, what I claim as new and desire to secure by Letters Patent of the United States is:

1. A fastening-inserting machine comprising a fastening-inserting tool, a horn movable heightwise of the machine thereby to present a shoe to the tool, a support on the horn constructed and arranged to enter the crease between the upper and sole of a shoe to support the shoe against the thrust of the tool, and a gage mounted upon the support for locating the shoe with the edge of the sole thereof in predetermined position laterally of the tool. 5

2. A fastening-inserting machine comprising a fastening-inserting tool, a horn, a support mounted on the horn constructed and arranged to enter the crease between the upper and sole of a shoe for supporting the shoe, a gage slidably mounted upon the support for locating the shoe with the edge of the sole thereof in predetermined position laterally of the tool, means for securing the gage to the support for movement therewith, and means for mounting the support for movement laterally of the tool. 15 20

3. A fastening-inserting machine comprising a fastening-inserting tool, a horn movable heightwise of the machine thereby to present a shoe to the tool, a plate carried by the horn and having a portion constructed and arranged to enter the crease between the upper and sole of a shoe to support the shoe against the thrust of the tool, a gage positioned upon the plate for locating the shoe with the edge of the sole thereof in predetermined position laterally of the tool, and means for mounting the plate and gage for adjustment laterally relatively to the horn and to each other. 25 30 35

4. In a fastening-inserting machine, a fastening-inserting tool, a horn movable heightwise of the machine thereby to present a shoe to the tool, a shoe support mounted upon the horn and having a portion thereof constructed and arranged to enter the crease between the upper and sole of a shoe to be operated upon, a gage slidably mounted upon the support for engaging the edge of the sole of the shoe to locate the sole in predetermined position laterally of the tool, means for securing the gage to the support, and stops for locating the support and gage in either of two positions laterally of the tool. 40 45 50

5. A fastening-inserting machine comprising a fastening-inserting tool, a horn movable heightwise of the machine thereby to present a shoe to the tool, a plate on the horn constructed and arranged to enter the crease between the upper and sole of a shoe to support the shoe against the thrust of the tool, a gage mounted upon the plate for locating the edge of the sole of the shoe in predetermined position laterally of the tool, and an auxiliary support having a portion constructed and arranged to enter the crease between the upper and the sole of the shoe at a point upon the other side of the shoe from the point of the engagement of the plate therewith. 55 60 65

6. A fastening-inserting machine comprising a fastening-inserting tool, a horn, a member slidably mounted upon the horn and constructed and arranged to enter the crease between the upper and sole of a shoe to be operated upon to support the shoe, a gage slidably mounted upon said member for engaging an edge portion of the sole in locating the same in operative position relatively to the fastening-inserting tool, means for securing the gage to said member, laterally 70 75 80 85 90 95 98

adjustable stops for readily locating said member in either of two positions laterally of the fastening-inserting tool, and means for locking said member and gage in adjusted position on the horn.

- 5 7. A fastening-inserting machine comprising a fastening-inserting tool, a spindle mounted for movement heightwise of the machine, a horn carried by the spindle, a shoe support carried by said horn constructed and arranged to enter the crease between the upper and the sole of a

shoe to be operated upon, a gage mounted upon the support for locating the edge of the sole of the shoe laterally of the fastening-inserting tool, an arm pivoted upon the spindle, a roll carried by the arm and arranged to enter the crease between the upper and the sole of the shoe for supporting the shoe at a point on the opposite side of the shoe from the point of engagement of the support therewith, and means normally operative to force the roll toward the support. 5
